UNITED STATES PATENT OFFICE

129,000

DESIGN FOR A HAT

Babette C. Tripp, New Haven, Conn., assignor to Leighton Hats, Incorporated, New York, N. Y., a corporation of New York

Application July 3, 1941, Serial No. 101,890

Term of patent 7 years

To all whom it may concern:

Be it known that I, Babette C. Tripp, a citizen of the United States, residing at New Haven, county of New Haven, and State of Connecticut, have invented a new, original, and ornamental Design for a Hat, of which the following is a specification, reference being had to the accompanying drawing, forming part thereof.

In the drawing—

Fig. 1 is a side perspective view of a hat showing my new design.

Fig. 2 is a side view of the hat shown in Fig. 1.
Fig. 3 is a top plan view thereof.

I claim:

The ornamental design for a hat, as shown.

BABETTE C. TRIPP.
